UNITED STATES PATENT OFFICE.

HERMAN ROSENTHAL, OF NEW YORK, N. Y.

BUCKLE.

1,121,403.

Specification of Letters Patent. Patented Dec. 15, 1914.

Application filed February 19, 1912. Serial No. 678,522.

To all whom it may concern:

Be it known that I, HERMAN ROSENTHAL, a citizen of the United States, residing at New York, in the county of New York and State of New York, have invented certain new and useful Improvements in Buckles; and I do hereby declare the following to be a full, clear, and exact description of the invention, such as will enable others skilled in the art to which it appertains to make and use the same.

This invention relates to buckles, and is particularly designed to improve the buckles now in use upon any garments of men, such as the side straps on trousers and the back upon the waistcoat.

Heretofore the buckles which have been used have the tines thereof arranged opposite to the strip of cloth they are adapted to engage, *i. e.*, that is, the pull exerted by the buckle is in the direction in which the tines extend. This construction often damages the cloth to such an extent that the same becomes absolutely useless by reason of the exceptional strain thereon.

It is the object of the present invention to overcome this objectionable feature by having the tines of the buckle extend in the direction in which the pull is exerted by the strip of cloth which they engage. This absolutely, by experiment, eliminates all damage to the strap engaged thereby and creates a strong, substantial buckle, which, by the elimination of strains thereon, constitutes a permanent connection between the buckle and the retaining strap.

With the above and other objects in view, this invention consists in the construction, combination and arrangement of parts, all as hereinafter more particularly described, claimed and illustrated in the accompanying drawings, wherein:

Figure 1 is an elevation of the straps co-operating with the buckle forming the subject matter of the present invention; Fig. 2 is a longitudinal section of a buckle and its co-operating strap; and Fig. 3 is a perspective view thereof.

The buckle forming the subject matter of the present invention comprises a plate having an obliquely arranged projection at one terminal thereof, which is provided with

a rectangular opening, which constitutes a keeper for the strap detachably connected to the buckle, and further provides a means for securing the retaining strap which passes through the rectangular opening formed in the body of the plate. At the opposite terminal of the plate is provided a pair of upwardly extending bearings, between which is pivoted a curved plate, said curved plate being provided with tines extending toward the rectangular opening formed within said plate.

Reference being had more particularly to the drawings, 10 indicates a retaining or supporting strap which is adapted to be in direct alinement with a similar strap 11, the free terminal of which is adapted to be retained by the buckle forming the subject matter of the present invention.

The buckle constituting the subject matter of the present invention comprises a plate 12 having formed therein a rectangular opening 13. One terminal of the plate 12 is bent upwardly at an angle and forms an oblique projection 14 which is likewise provided with a rectangular opening 15, said opening constituting a keeper for the free terminal of the strap 11. At the opposite terminal of the plate 12 is provided a plurality of outwardly extending bearings 16 which are arranged at right angles to the body of the plate 12. An inwardly curved plate 17 is journaled in the bearings 16 and has formed on its inner surfaces a plurality of tines or teeth 18. The terminal of the strap 10 passes through the opening 15 of the projection 14 and is bent upon itself about the bar separating the openings 13 and 15 extending through said opening 13, and is secured to the body portion of the strap 10. The free terminal of the strap 11 is adapted to pass under the plate 17 and through the opening 15 of the projection 14 and be engaged by the tines 18 of said plate, and is thereby rigidly retained in co-operative position with the buckle.

Having thus fully described my invention, what I claim as new, and desire to secure by U. S. Letters Patent, is:

A buckle comprising a frame provided with a plane base member at one end having upwardly bent pintle bearing ears, a curved

tongue plate having pintles pivoted in said ears at one end of the buckle frame and provided with projecting strap engaging prongs, said frame having a cross bar in the same plane as the base member and a tuck loop comprising a bar offset from the plane of the base member at the end of the buckle opposite the tongue plate, and the tongues

of said plate projecting toward said tuck loop when in closed position.

In testimony whereof I affix my signature in presence of two witnesses.

HERMAN ROSENTHAL.

Witnesses:

CHARLES S. WILSON,
CHAS. R. SCHRAPPS, Jr.
